WALL HYDRANT

Joseph C. Woodford, Spring Lake, Mich., assignor to
Woodford Manufacturing Company, Des Moines, Iowa,
a corporation of Iowa

Filed Aug. 21, 1968, Ser. No. 13,229

Term of patent 14 years

Int. Cl. D23—01

U.S. Cl. D23—12

FIG. 1

FIG. 2

FIG. 3

FIG. 4

FIGURE 1 is a perspective view of a wall hydrant showing my new design;

FIGURE 2 is a front elevational view of a modified form of the wall hydrant shown in FIGURE 1;

FIGURE 3 is a front elevational view of a second modified form of the wall hydrant shown in FIGURE 1; and

FIGURE 4 is a front elevational view of a third modified form of the wall hydrant shown in FIGURE 1.

I claim:

The ornamental design for a wall hydrant, as shown and described.
